DEVICE FOR SUPPLYING FASTENER ELEMENTS

Josef Lindner, Nuremberg, Germany, assignor, by
means assignments, to Metallbesatz Willy
Klotzer & Co., Nuremberg, Germany, a company
of Germany

Application December 15, 1937, Serial No. 180,009
In Germany September 28, 1936

5 Claims. (CL. 153—1)

This invention relates to devices for supplying fastener elements, said devices forming parts of machines for the manufacture of slide fasteners.

As contrasted with supply devices which include a chute or groove through which the fastener elements are carried towards the place at which they are fixed to a carrier ribbon, the present invention utilizes a guide rail having a thickened rim, the fastener elements being supported one above the other in a pile with their arms slidably engaging said thickened rim of said rail.

A further feature of this invention consists in the provision of two alternately actuated feeding slides cooperating with the elements of the pile carried by the aforementioned rail in such a way that one slide grips the lowermost element of the pile and carries the same towards the place at which it is fixed to the carrier ribbon, while the other slide keeps the element next to said lowermost element in fixed position. This feeding slide serves for carrying said fastener elements in succession to the place at which they are fixed to carrier ribbons forming part of the completed slide-fastener.

According to a further feature of this invention, said slide may be provided at its head-piece with oppositely acting pressure members, acting simultaneously as a device for fixing said elements to the carrier ribbon and for compressing the arms of the forwardly carried fastener elements after being placed to ride on the thickened rim of the carrier ribbon, thus fixing the elements to the latter.

By means of the supply-device in the form of a rail with one thickened rim there is secured the further advantage that the pile of superposed fastener elements carried by said rail will move in smooth sliding contact thereon and practically without any impediment during their travel towards the feeding slide which carries the elements to the fixing device.

Proper feeding of the fastener elements, especially those of light weight material such as aluminum, is thus attained, because the several elements of the pile carried by said rail in superposition will impose a load especially on the under elements of the pile to move the latter downward on the vertically positioned rail.

By means of a pair of alternately actuated slides provided at the lower end of said rail, feeding motion is imparted to the element which is at the time in lowermost position in the pile by one of said slides, while the element at the time positioned above said lowermost element and

therewith all further elements are kept fixed on said rail by the other of said slides.

The first-mentioned slide which serves for feeding the lowermost element towards the carrier ribbon may also be provided with means for compressing the arms of a fastener element when riding on the thickened rim of the carrier ribbon, thereby not only supplying the elements individually to said ribbon but also serving to fix said elements to the latter. There is consequently attained a further simplification of the machine in dispensing with a special controlled fixing device.

As the slide which serves for successive feeding of the elements and the device for fixing the latter to the carrier ribbon are thus combined with each other, there is not only attained a simplified drive but also a quite considerable increase of the speed of operation and especially of the procedure of fixing the elements to the carrier ribbon.

In the accompanying drawings there are shown some examples of novel constructions of feeding and fixing devices for the fastener elements constructed in accordance with my invention, and wherein

Figure 1 is a side elevation partly in section of separate or individual supply and fixing mechanisms for the fastener elements;

Figure 2 is a top plan view thereof with parts in section;

Figure 3 is a side elevation of a modified form of apparatus embodying a combined supply and fixing mechanism;

Figure 4 is a top plan view thereof and illustrating the parts in feeding position;

Figure 5 is a similar view but illustrating the parts in fixing position;

Figure 6 is a longitudinal sectional view through the supply slide; and

Figure 7 is a front elevation of the fixing mechanism illustrated in said modified form of apparatus.

As illustrated in Figs. 1 and 2, the supply device consists of a vertically disposed rail 1 that is carried by a base-plate 11. One longitudinal edge of said rail is thickened to form a bead 2 as shown in a side-view in Fig. 1 and in cross-section in Fig. 2. The several fastener elements 3 are supplied to said rail 1 by means of a sorting device arranged above said rail but not shown in the drawing, in such a manner that the several elements will be superposed upon each other in a pile on said rail 1. The arms of the fastener elements 3 of said pile grip around the thickened

rim 2 of said rail 1 and will thus be safely guided by the latter so that they will move by action of gravity downward without any frictional impediment. Feeding motion towards the fixing device is imparted to the lowermost element of the stack by means of two slides 4 and 5 which at their ends facing the fastener elements are of the form of a fork, said slides 4 and 5 being mounted slidably within guides 6 and 7. In operative position the forked ends of both slides 4 and 5 grip round the two undermost fastener elements, the respective slide and fastener element gripped thereby being positioned within the same plane.

15 The thickness of the slides 4 and 5 is equal to the thickness of a fastener element. In operation the upper slide 4 moves forward slightly and engages the element next to the lowermost element of the pile, exerting sufficient pressure thereagainst to maintain said element in fixed position on the aforesaid rail 1 with the thickened rim 2, while the lowermost element will be released from said rail 1 and moved by means of said lower slide 5 past the lower end of said rail 1. The rail 1 with the thickened rim 2 may be fixed on the wall 8 of an angularly shaped support 9, said wall 8 being provided at its lower portion with an aperture 10 permitting passage of said slides 4 and 5 therethrough.

20 As soon as the lower slide 5 is advanced to its forward fixing position towards the rotating disk 13 the upper slide 4 is slightly retracted so that the fastener element held thereby is released and in consequence thereof the pile of elements will move downward a distance corresponding to the thickness of an element. Thereby the lowermost element descends in the space between slides 4 and 5. Later at the end of the retractive movement of slide 5 this lowermost element will fall into the forked end of this slide; the upper slide 4 serving again as a support for the pile of elements. Through the following forward movement of slide 5 this lowermost element will be carried forward towards the carrier ribbon 14. This operation repeats itself continuously in like manner, the control of the two slides 4 and 5 being effected by proper mechanical means. The carrier ribbon 14 with its thickened rim 15 is intermittently moved past the place of supplying the elements thereto in such a manner that the several elements will subsequently be placed onto said carrier ribbon 14 round the thickened rim 15 thereof in proper distances from each other to ride on the latter. In the present example of construction it is assumed that the carrier ribbon is fed forward by means of an intermittently rotating disk 13 provided with teeth and interstices therebetween as indicated at 12 and that the elements 3 after being placed onto the carrier ribbon are fixed thereto by means of a pair of pressure members 16 which subsequently to placing an element onto the carrier ribbon will compress the two arms of said element to fix the latter to said carrier ribbon.

25 The elements are thus supplied in succession to their carrier ribbon by means of a special feeding device in form of the two slides 4 and 5 and thereupon fixed to said carrier ribbon by means of a special pressure device in form of the two pressure members 16 which are operated in unison with the motion of the slides 4 and 5. However the supply device may be constructed to simultaneously act as pressure device for fixing the elements to the carrier ribbon 14, as indicated in

30 Figs. 3-7.

Referring to Figs. 3 to 7, the slide 5a is mounted on the base plate 11 and guided thereon by the aid of a slide-head 5'. This slide-head 5' carries a pressure bridge 17 which is supported on and longitudinally displaceable with spring pressed 5 rods 18. On the pressure bridge 17 there are provided two oppositely disposed co-operating pressure-levers or jaws 16a pivoted near their inner ends at 20 to said pressure bridge 17 and near their outer ends to laterally projecting arms of 10 the slide-head 5'. Intermediate said pressure members 16 there is provided a gap 3' into which the lowermost element may move, whenever it is released from the pile of elements on said rail 1. The gap 3' between said pressure levers 16 is closed 15 up in downward direction by a moveable tongue 21 mounted so as to be longitudinally displaceable on said pressure bridge 17 and kept fixed by a resiliently supported rod 19 on said slide-head 5'. The tongue 21 thus will represent a support 20 which serves to keep the fastener element at the time positioned within said gap 3' fixed between said pressure levers 16a. In rearward position of the slide-head 5', as shown in Figs. 3 and 4, the pressure levers 16a are in inoperative condition 25 and in position below the rail 1, so that a fastener element released from the latter will drop into said gap 3'. Now the slide-head 5' moves forward with the result that the respective fastener element between the jaws 16a is fed forward to 30 the carrier ribbon 14 placed on the intermittently rotated disk 13 and moves past the supply device.

As the slide head 5' moves forwardly, the jaws 16a supporting the element 3 on either side, and the pressure bridge 17 embracing the rear of the 35 element, remain in the relative positions shown in Figure 4 until the element 3 engages the rim or bead 15 on the carrier ribbon 14 carried by the rotating disc 13. The pressure bridge is adapted to withstand only a predetermined pressure which 40 may be regulated by adjusting the springs on the rods 18. Thus, after the element 3 has engaged the carrier ribbon 14, the continued forward movement of the slide head 5' causes this predetermined pressure to be exceeded, whereupon the 45 movement of the bridge 17 is arrested while the slide head 5' continues to advance. As each of the jaws is pivoted at one end to the still moving slide head 5', and near its other end to the now stationary pressure bridge 17, said jaws are caused 50 to rock to the position shown in Figure 5, thus compressing the two gripping arms of the element 3 and affixing the latter to the carrier ribbon 14.

As the slide-head moves again back into its initial inoperative position, the pressure levers 55 16a will likewise return to inoperative or open position for the reception of a new fastener element to carry it underneath the rail 1.

The tongue 21 moves against the action of its spring towards the rear, when on forward motion 60 of the slide-head it abuts the thickened rim 15 of the carrier ribbon 14 and again moves forward, whenever said slide-head returns into its rearward position underneath the rail 1.

In order to support the pile of fastener elements 3 on the rail 1 there is likewise provided a second slide 4a which exerts a pressure against the lowermost element of said pile and preventing further downward sliding of the latter.

The slide 4a is assumed as being of two-part 70 construction in the example shown in Figs. 3 to 7, the two slide-parts 4a and 4' being alternately moved within the guides 23 and connected with each other by means of a transverse double-armed lever 22 swingable about a fixed 75

bearing point. The one slide-part 4' may extend with a stop provided thereon into the path of motion of the slide-head 5' and may properly be actuated upon rearward adjustment of the latter.

By this the two slide-parts 4a and 4' will alternately act against the fastener element 3 which at the time forms the lowermost element of the pile on the rail 1, thus effecting in operation with the supply and fixing device 5' a properly controlled supply and fixing of individual elements to the carrier ribbon 14.

I claim:

1. In a machine for supplying and affixing slide fastener elements from a magazine to an intermittently advancing tape, a combined ejector and fastening device for said elements, comprising a reciprocable slide head for receiving and delivering successive fastener elements from said magazine, a cross member carried by said slide head and longitudinally displaceable thereon, spring means normally preventing displacement of said cross member, means for reciprocating said slide head, whereby upon the forward movement of the latter said cross member will be displaced as the fastener element engages said tape, a pair of opposed jaw members pivoted to said slide head and spaced apart to accommodate said fastener element, said jaw members being operatively connected to said cross member, whereby upon displacement of the latter on said head, said jaws are compressed about said element to affix the same to said tape, and means to support the elements between the jaws during their transfer to the tape.

2. In a machine for supplying and affixing slide fastener elements from a magazine to an intermittently advancing tape, a combined ejector and fastening device for said elements, comprising a reciprocable slide head for receiving and delivering successive fastener elements from said magazine, a cross member carried by said slide head and longitudinally displaceable thereon, spring means normally preventing displacement of said cross member, means for reciprocating said slide head, whereby upon the forward movement of the latter said cross member will be displaced as the fastener element engages said tape, a pair of opposed jaw members pivoted to said slide head and spaced apart to accommodate said fastener element, said jaw members being operatively connected to said cross member, whereby upon displacement of the latter on said head, said jaws are compressed about said element to affix the same to said tape, and a slideable tongue adapted to normally lie beneath the space between said jaws for supporting said element, said tongue being displaceable longitudinally as said slide head advances to said fixing position and means for returning said tongue upon reverse movement of said slide head.

3. In a machine for supplying and affixing slide fastener elements from a magazine to an intermittently advancing tape, a combined ejector and fastening device for said elements, comprising a reciprocable slide head for receiving and delivering successive fastener elements from said magazine, a cross member carried by said slide head and longitudinally displaceable thereon, spring means normally preventing displacement of said cross member, means for reciprocating said slide head, whereby upon the forward movement of the latter said cross member will be displaced as the fastener element engages said tape, a pair of opposed jaw members pivoted to said slide head and spaced apart to accommodate said fastener element, said jaw members being operatively connected to said cross member, whereby upon displacement of the latter on said head, said jaws are compressed about the element to affix the same to the tape, and displaceable means adapted to normally lie beneath the space between said jaws for supporting said element and being displaced as the slide head advances to said fixing position.

ward movement of the latter, said cross member will be displaced by the engagement of said fastener element with said tape, a pair of opposed jaw members pivoted to said slide head and spaced apart to accommodate said fastener element, said jaw members being operatively connected to said cross member, whereby upon displacement of the latter, said jaws are compressed about said element to affix the same to said tape and means adjacent the lower end of said magazine cooperative with said slide head for successively feeding elements from said magazine to said jaws, and means to support the elements between the jaws during their transfer to the tape.

4. In a machine for supplying and affixing slide fastener elements from a magazine to an intermittently advancing tape, a combined ejector and fastening device for said elements, comprising a reciprocable slide head for receiving and delivering successive fastener elements from said magazine, a pressure bridge member carried by said slide head and longitudinally displaceable thereon and arranged for engagement with the rear edge of the elements, spring means normally preventing displacement of said pressure bridge member, means for reciprocating said slide head, whereby upon the forward movement of the latter said pressure bridge member will be displaced as the fastener element engages said tape, a pair of opposed jaw members pivoted to said slide head and spaced apart to accommodate said fastener element, said jaw members being operatively connected to said pressure bridge member, whereby upon displacement of the latter on said head, said jaws are compressed about said element to affix the same to said tape, and a slideable tongue adapted to normally lie beneath the space between said jaws for supporting said element, said tongue being displaceable longitudinally as said slide head advances to said fixing position.

5. In a machine for supplying and affixing slide fastener elements from a magazine to an intermittently advancing tape, a combined ejector and fastening device for said elements, comprising a reciprocable slide head for receiving and delivering successive fastener elements from said magazine, a pressure bridge member carried by said slide head and longitudinally displaceable thereon and arranged for engagement with the rear edge of the elements, means for normally preventing displacement of the pressure bridge member, means for reciprocating said slide head, the arrangement being such that upon the forward movement of the slide head said pressure bridge member will be displaced relative to the slide head as a result of the bridge member being stopped by engagement of the element with the tape, a pair of opposed jaw members pivoted to said slide head and spaced apart to accommodate said fastener element, said jaw members being operatively connected to said pressure bridge member whereby upon displacement of the latter relative to the head member said jaws are compressed about the element to affix the same to the tape, and displaceable means adapted to normally lie beneath the space between said jaws for supporting said element and being displaced as the slide head advances to said fixing position.

JOSEF LINDNER.
